SIDE-PLUG HYDRAULIC CELLAR GATE

Frank J. Schweitzer, Jr., Brea, Calif.

Application October 27, 1947, Serial No. 782,363

1 Claim. (Cl. 137—139)

1

This invention is a cellar control gate; that is, it is a form of valve used in deep well operations to make a complete shut off of fluid flow in a well casing, or to close onto an installed production pipe in a well.

Control gates of this general type include inner closure or ram assemblies which are often operated by hydraulic or other fluid pressure. A serious objection to some forms of pressure fluid operated gates is the great amount of time and labor involved in assembling the rams and their attached power source and the usual practice of removing the piston and its pressure chamber whenever a ram assembly is removed for any reason. Moreover, such a ram and power plant hook-up makes for constructional expense.

Therefore, an object of this invention is to provide a cellar control gate and power hook-up which wholly eliminates the need of dismounting the power plant merely to enable the insertion, adjustment or removal of a gate assembly.

A further object of the invention is to provide a control valve or gate structure in which the ram assembly is of such form of installation in the gate shell that the assembly can be laterally shifted from the shell at will while its fluid operated power plant remains permanently sealed in its normal place of attachment on and to the shell.

Also, an object of the invention is to provide for the easy, safe and effective intercoupling of the removable ram assembly, and for the ready disconnection of the assembly, as to its operating piston or other actuating device, as the case may be. And, in this connection, it is an object to provide a ram connection of such type that there are no extraneous fasteners, couplings or specially adjustable hitching parts included, or needing manipulation.

To secure simplicity, low cost of construction and utmost ease of interconnecting a gate assembly, as it is installed, and as easy removal, a feature of the invention is to provide a connecting device of such a form that it is only necessary to bodily shift a ram assembly into its normal position in the gate shell whereby to secure full, reliable and direct interconnection of the assembly to a complementary part of the fixed, sealed and readied power plant.

The invention resides in certain advancements in this art as set forth in the ensuing disclosure and having, with the above, additional objects and advantages as hereinafter developed, and whose constructions, combinations and detail of means and the manner of operation will be made

2

manifest in the following description of the here-with illustrative embodiment; it being understood that modification, variations and adaptations may be resorted to within the scope, spirit and principles of the invention as it is claimed in conclusion hereof.

Figure 1 is a partial, longitudinal section and plan.

Figure 2 is a partial, vertical, axial section and elevation.

Figure 3 is a broken away, plug-side elevation; certain plugs being removed to permit insertion or removal of a gate assembly.

Figure 4 is a sectional detail of the ram assembly and piston rod connection.

The illustrated control gate embodies a substantial, cuboidal main body or shell 2 having top and bottom faces 3 and 4 for attachment of desired well head fittings, not shown. A large bore hole 5 passes from top to bottom of the shell for reception of tools or pipe, as needed. The bore hole is intersected by an upper chamber 6 in which is longitudinally operative a pair of opposed and cooperative closure or gate assemblies, of which only the right-hand assembly 7 is shown and which is of a form to close tightly onto a pipe when disposed (centrally) in the shell bore hole 5.

In a lower longitudinal chamber 8 is operative a pair of opposed and cooperative ram assemblies 9, of which only the right-hand one is shown; Fig. 1, being in outer operational position as to the hole 5. The ram assembly 7 is shown in Fig. 2 in its innermost position.

Rigidly fixed on opposite ends of the shell 2 are dual, right-hand and left hand cylinder blocks 10 and 11, which are substantially permanently installed in that they do not have to be removed either for installation or removal of the mentioned ram assemblies.

In the upper cylinder chambers 12 of the said blocks are power pistons 13 (only the right-hand one being shown). The piston 13 has a rigidly affixed piston rod 14 working through its chamber wall 15. The rod 14 is axially threaded at 14t and receives a complementary threaded portion of a tail-rod 16 extending axially from the piston 13 and through the cylinder head 17; its outer end being flattened at 16f for application of a tool whereby to rotate the rod and effect axial motion of the piston rod 14, when and if necessary.

A distinguishing feature of this invention is the construction and arrangement of parts for the reliable connection of each piston in the control gate to its relative control valve or ram as-

sembly, and for the insertion or removal of any gate ram assembly from the shell 2 without disturbing the rigidly attached power cylinder blocks; which may be integral with the shell if desired.

Therefore one side of the shell is provided with a suitable number of windows 20, one for each ram assembly is very practical, one longitudinal pair of the windows opening into the upper valve chamber 6 and the lower pair opening into the lower chamber 8, so that each window will expose its respective, installed assembly. Each window is tightly closeable by its respective plug 21 which is fixable by bolts 22.

Means are provided whereby to interconnect each ram assembly to its respective piston rod by the mere straight shift of an assembly in through its shell window and into the intersecting upper or lower valve chamber, as the case may be; disconnection is had by an opposite or extracting operation of the ram assembly. The description of one such connection will suffice for all since they are alike. Each ram assembly includes a body block (9') Fig. 4, having a T-section channel 9c provided in and along its face opposite the inwardly projecting end of its relative piston rod. Each such rod has a rectangular, transverse head or spline 25, Fig. 4, slidably fitting in the presented channel 9c of an assembly as such a block is pushed in through a window 20 while the piston spline 25 is at the outer and registering position to enter the near end of the block channel 9c, Fig. 3.

The spline 25 thus constitutes a device slidably interlocking the inner end of a piston rod to an assembly block and prevents the piston rod from rotating with the tail rod 16 should it be necessary at any time to effect outward movement of an assembly 9, as in the absence of motive pressure fluid in a piston chamber.

The open gate 9', Fig. 3, is in register with the window 20 and its top and bottom faces align with and are guided by the cooperative, respective inside top and bottom guide faces of the chamber 8, as seen in Fig. 2, at gate 9. The top 45

and bottom faces of the gate 9-9' fit the respective faces of the window 20 whose top and bottom faces are coplanar with the gate guide faces as clearly seen in Fig. 2, at gate 9.

5 Normally the gate assemblies are shifted in either direction by operation of the power pistons, in which event the tail rods merely reciprocate with the pistons (without screw function). Each gate ram assembly has its own power piston, and 10 either upper or lower pair of the assemblies can be power driven concurrently if desired.

The principle of lateral insertion or removal of the several ram assemblies without need of removal of any part of the actuating pistons and 15 cylinders, or their rods, and the manner and the means of connecting each assembly to its rod is made clear in the above disclosure.

What is claimed is:

20 A side-closing, well cellar gate assembly characterized by and including a shell having a flow hole from top to bottom and a gate chamber opening laterally from said hole and having inner top and bottom gate guiding faces and a ram gate slidably fitting said faces and having an 25 axis of motion at a right angle to the axis of said hole for opening and closing functions; said shell having a side window whose top and bottom faces are coplanar with said chamber faces and said window being located at the locale of valve 30 open position in the shell, and a side closure for the window.

FRANK J. SCHWEITZER, JR.
